(57) **CLAIM**

The ornamental design for a scraper tool, as shown and described.

DESCRIPTION

FIG. 1 is a perspective view of a scraper tool;
FIG. 2 is a front elevational view thereof, in which a detailed view is taken and shown in FIG. 3;
FIG. 3 is a detailed front elevational view thereof, in which a sectional view is taken and shown in FIG. 4;
FIG. 4 is a sectional view taken at 4-4 in FIG. 3 thereof;
FIG. 5 is a right side elevational view thereof, the left-side elevational view being a mirror image;
FIG. 6 is a top plan view thereof;
FIG. 7 is a bottom plan view thereof; and,
FIG. 8 is an exploded view thereof, showing the head removed from the handle.
The broken line showing of a scraper tool handle is for the purpose of illustrating environmental structure and forms no part of the claimed design. The other broken lines in the figures depict threads that form no part of the claimed design.
